UNITED STATES PATENT OFFICE

163,600

IRON STAND

Joseph Alexandre Hebert, Montreal, Quebec,
Canada

Application March 21, 1951, Serial No. 14,571

Term of patent 7 years

(Cl. D49—6)

To all whom it may concern:

Be it known that I, Joseph Alexandre Hebert, citizen of Canada, residing at 8193 St. Denis Street, Montreal, Canada, have invented a new, original, and ornamental Design for Iron Stand, of which the following is a specification, reference being had to the accompanying drawing, forming part thereof.

Fig. 1 is a plan view of an iron stand, showing my new design;

Fig. 2 is a front elevational view of the same;
Fig. 3 is a side elevation view of the same.

I claim:

The ornamental design for an iron stand, as shown.

JOSEPH ALEXANDRE HEBERT.
